UNITED STATES PATENT OFFICE.

JAMES R. HOLCOMB, JOHN D. HOLCOMB, AND CHARLES F. HOLCOMB, OF
MALLET CREEK, OHIO.

TELEPHONE.

SPECIFICATION forming part of Letters Patent No. 240,713, dated April 26, 1881.

Application filed February 19, 1881. (No model.)

To all whom it may concern:

Be it known that we, JAMES R. HOLCOMB, JOHN D. HOLCOMB, and CHARLES F. HOLCOMB, citizens of the United States, residents 5 at Mallet Creek, in the county of Medina and State of Ohio, have invented certain new and useful Improvements in Telephones; and we do hereby declare the following to be a full, clear, and exact description of the invention, 10 such as will enable others skilled in the art to which it appertains to make and use the same, reference being had to the accompanying drawings, and to letters or figures of reference marked thereon, which form a part of this 15 specification, in which—

Figure 1 is a front view. Fig. 2 is an inside view. Fig. 3 is a cross-section of the device. Fig. 4 is a view of the insulator.

This invention relates to telephones of the 20 class known as "mechanical."

The object of the invention is to obtain a very sensitive and powerful telephone combining loudness and clearness with freedom from the lateral ringing vibrations so common in 25 telephones of this class.

To this end the invention consists in the construction hereinafter described.

In the annexed drawings, A is a box, made of light sonorous wood or other equivalent 30 material, to add to the power of the voice by the resonance.

a is the outer face of the box, back of which is located the diaphragm-receiving board B.

a' is a circular opening in face a, and b is 35 another, registering therewith in board B.

C C' are the diaphragms, which are fastened by their edges c c', one to the inside, the other to the outside, of board B, said diaphragms being stretched across opening b, 40 having an air-space, z, between them, being held apart at their centers by a small button, n, and having the concavo-convex shape shown.

D is the line-wire, having loop d, and passing through the diaphragms C C' at their centers, and connected to the call-button E at the outside. By striking on this button the diaphragms are vibrated, which vibrations will be communicated to the receiver at the end of the line and give an alarm.

F F are two wires, crossing each other and 50 attached to the line-wire D at loop d. The ends f of these wires are attached to the sliding cross-bars G G, which are regulated by the screws H, by which they may be drawn in and out, by which means the diaphragms can be 55 given a high and uniform tension. By these tension devices the shape of the diaphragms is preserved, and at need the same can be varied by operating the screws.

I is an insulator or support for the line-wire, 60 consisting of a loop of spring-wire bent in an oval shape, with loop i at the top for attaching to wire that attaches to pole and hook l and eye m on side, whereby it can be easily hooked on the line-wire. 65

The air-space between the diaphragms acts as a damper to destroy the lateral or ringing vibrations. The resonant box and two diaphragms, with this intervening cushion, form a device which is sensitive and produces a 70 clear and loud sound.

The insulator renders it unnecessary to cut the line-wire or to slip it on from the end, the loop being simply hooked on.

What we claim is—

1. In a telephone, the combination of a box, having an opening and two parallel concavo-convex diaphragms, with air-chamber between extending across said opening.

2. In a telephone, the diaphragm, in combination with the tension-wires and adjusting-bars located within the box, and the wires connecting the diaphragm with the bars, whereby the movement of the latter controls the position of the diaphragms. 80

3. An insulator consisting of a loop having an eye at one end and a hook and eye to the side.

In testimony whereof we affix our signatures in presence of two witnesses.

JAMES R. HOLCOMB.
JOHN D. HOLCOMB.
CHARLES F. HOLCOMB.
